FINGER RING

Mario Michelotti, Chicago, Ill., assignor to Central Monogram Works, Inc., Chicago, Ill., a corporation of Illinois

Filed Feb. 21, 1964, Ser. No. 78,724

Term of patent 14 years

(Cl. D45—10)

FIG. 1 is a perspective view of a finger ring embodying my new design;

FIG. 2 is a front elevational view thereof;

FIG. 3 is a top plan view thereof;

FIG. 4 is a rear elevational view thereof; and

FIG. 5 is an enlarged sectional view taken on the plane of line 5—5 and viewed in the direction indicated.

The essential features of my design reside in the portions shown in solid lines.

I claim:

The ornamental design for a finger ring, substantially as shown and described.
